UNITED STATES PATENT OFFICE.

EDWIN SMITHE, OF GLOUCESTER, MASSACHUSETTS.

COUGH REMEDY.

SPECIFICATION forming part of Letters Patent No. 438,955, dated October 21, 1890.

Application filed February 19, 1890. Serial No. 341,066. (No specimens.)

To all whom it may concern:

Be it known that I, EDWIN SMITHE, a citizen of the United States, and a resident of Gloucester, in the county of Essex and State of Massachusetts, have invented new and useful Improvements in Cough-Lozenges, of which the following is a specification.

My invention relates to a new and useful medical compound to be used in the form of lozenges in cases of coughs, colds, and all diseases of the throat and lungs.

My compound consists of the following ingredients, combined in about the proportions stated, viz: sugar, one cup; honey, one-half cup; cod-liver oil, two table-spoons; corn-starch, two table-spoons; glucose, two table-spoons; taro, one dessert-spoon.

The manner in which I prepare this compound is as follows: The ingredients are thoroughly intermixed with suitable flavoring and stirred until it forms a paste, which is boiled and pulled in the manner of making certain kinds of candy, and finally molded in suitable forms or cut into the shape of tablets or lozenges. The corn-starch and taro subserve the purpose of holding the oil in the confectionery, for without the corn-starch and taro the oil would flow out as soon as the confectionery cooled.

In case of a cough a lozenge composed of 30 the composition described is to be taken every hour until a cure is effected.

Having thus described my invention, what I wish to secure by Letters Patent and claim is—

The herein-described medical compound for coughs, colds, and throat and lung diseases generally, consisting of sugar, honey, cod-liver oil, corn-starch, glucose, and taro, with a suitable flavoring added, substantially in the 40 proportions specified.

In testimony whereof I have signed my name to this specification, in the presence of two subscribing witnesses, on this 15th day of February, A. D. 1890.

EDWIN SMITHE.

Correction in Letters Patent No. 438,955.

It is hereby certified that the name of the patentee in Letters Patent No. 438,955, granted October 21, 1890, for an improvement in "Cough Remedies," was erroneously written and printed "Edwin Smithe," whereas said name should have been written and printed Edwin Smith; and that said Letters Patent should be read with this correction therein that the same may conform to the record of the case in the Patent Office.

Signed, countersigned, and sealed this 2d day of December, A. D. 1890.

[SEAL.]

CYRUS BUSSEY,
Assistant Secretary of the Interior.
